United States Patent Office.

GEORGE W. R. POLLOCK, OF BOSTON, MASSACHUSETTS.

Letters Patent No. 90,575, dated May 25, 1869.

IMPROVED SPRING BURGLAR-ALARM FOR DOORS.

The Schedule referred to in these Letters Patent and making part of the same.

To all whom it may concern:

Be it known that I, GEORGE W. R. POLLOCK, of Boston, in the county of Suffolk, and State of Massachusetts, have invented a Combined Door-Spring and Alarm; and I do hereby declare that the following, taken in connection with the drawings which accompany and form part of this specification, is a description of my invention, sufficient to enable those skilled in the art to practise it.

In this invention, I so combine a door-spring with an alarm, or noise-giving apparatus, that movement of the door in either direction sounds an alarm, the door being operated against the spring in opening, producing tension of the spring, which, in its reaction, closes the door when the force applied to open it is removed.

Figure 1, of the drawings, shows my combination in reversed plan, one part, or plate *e* of the casing being removed, to exhibit the interior.

Figure 2 is a sectional elevation, the section being taken in the plane of the line *z z*, fig. 1.

In the casing *a* is located, so as to freely turn on a shaft, *b*, a pulley, *c*, to which is attached a cord, *d*, by one end, the cord being coiled around the pulley, and having its other end projecting through the casing *a*, so that said projecting end may be attached either to the door or to the door-frame, or some part adjacent there-

to, according as the casing *a* is fixed to the door or to the door-frame.

In the casing the helical spring *f* is fixed by one end thereto, and by the other end to the pulley *c*, so that when, by opening the door, with which the string is connected, it is caused to unwind, and turn the pulley, it does so against the resistance of spring *f*, which is thereby coiled more closely, or is wound up.

On the pulley *c* is fixed the star-wheel *g*, so that it rotates with the pulley, and to the case *a* is riveted the spring *h*, so that its free end enters between the projections of the star-wheel, which, when the wheel is made to revolve, strike against and vibrate the spring in the manner of a watchman's rattle, producing a similar noise; and this is effected whether the star-wheel is rotated in one or the other direction, so that it will be obvious that the alarm will be sounded both in the opening and the closing of a door to which it is attached.

I claim the combined door-spring and alarm, constructed and arranged as described, so as to close the door with which it may be connected, and to sound an alarm both in the opening and in the closing of the door.

Witnesses: GEORGE W. R. POLLOCK.
